UNITED STATES PATENT OFFICE.

EMIL H. FISCHER, OF MILWAUKEE, WISCONSIN, ASSIGNOR TO H. C. MILLER CO., OF MILWAUKEE, WISCONSIN, A CORPORATION OF WISCONSIN.

LOOSE-LEAF BINDER.

Application filed August 7, 1922. Serial No. 580,254.

To all whom it may concern:

Be it known that I, EMIL H. FISCHER, a citizen of the United States, and resident of Milwaukee, in the county of Milwaukee 5 and State of Wisconsin, have invented certain new and useful Improvements in Loose-Leaf Binders; and I do hereby declare that the following is a full, clear, and exact description thereof.

10 My invention relates to loose leaf binders and more particularly to means by which the posts are secured to the binder strip.

The general object of the invention is to provide an improved means of simple construction by means of which the post is firmly secured against displacement relative to the strip and at the same time provide a structure which may be easily and cheaply manufactured.

20 Specifically, the invention includes means for preventing a rotary movement of the post with respect to the binder, as well as preventing longitudinal and angular displacement.

25 In the accompanying drawing:

Figure 1 represents a view partly in section and partly in elevation of one form in which my invention may be embodied.

Figure 2 is a bottom plan view of the 30 structure shown in Figure 1.

Figure 3 is a view similar to Figure 1, but showing a modified form.

Figure 4 is a sectional plan view taken on the line 4—4 of Figure 3.

35 Figure 5 is a view similar to Figure 1, but showing a further modification.

Figure 6 is a bottom plan view of the device shown in Figure 5.

Figure 7 is a view similar to Figure 1 40 showing a still further modification.

Figure 8 is a sectional view taken at right angles to the plane of Figure 7.

Figure 9 is a view similar to Figure 1, but showing a still further modification, 45 and

Figure 10 is an end elevation of the device shown in Figure 9.

Referring more particularly to the drawing, the numeral 1 indicates a binder strip 50 having a side flange and a back flange, the binder posts 2 being secured to and upstanding from the side flange.

In the forms shown in Figures 1 to 6, inclusive, the post is formed at its lower end 55 with tongues 3, which extend laterally and

outwardly and are countersunk in the under side of the binder strip. The post is, also, provided with laterally extending tongues 4 which may be conveniently disposed transversely of the tongues 3 and extend above 60 and engage the surface of the strip 1. It will be understood that the post may be inserted and firmly secured to the strip at a single operation, the lower tongues 3 being countersunk will prevent the rotary movement of the post and in conjunction with the upper tongues 4 will securely prevent 65 longitudinal or angular displacement.

In the form shown in Figures 3 and 4, portions of that part of the strip which is 70 punched out to receive the post are turned upwardly, as shown at 5, and form additional means for securing the post firmly against angular displacement due to lateral rocking.

75 In the modification illustrated in Figures 5 and 6, tongues 6 are cut out of the strip 1 and folded underneath the countersunk tongues 3. Preferably, the tongues 4 are, also, used to prevent angular transverse 80 displacement.

In the form shown in Figures 7 and 9, the tongues 7 are inserted through slots in the binder strip and are turned inwardly toward each other, being preferably countersunk in 85 the central portion 8 of the strip. A flange 9 is, also, formed integral with the strip and is turned underneath the tongues 7 to secure the post against longitudinal displacement.

90 In Figures 9 and 10 the tongues 3 are used and the strip 1 is made with a side portion somewhat wider than in the other forms shown, which is folded longitudinally so as to provide a reinforcing flange 10, 95 which, also, secures the post against longitudinal displacement.

It will be seen that all of the forms above described embody broadly the same principles and are embodied in the claims hereunto appended. It will, also, be understood that other modifications may be devised by means of which the principles of the invention may be carried out. It is, therefore, my intention to include all such modifications which fall within the scope of the claims.

I claim:

1. In a loose leaf binder, a metallic binder strip having a post upstanding therefrom,

the lower end of the post having lateral projections engaging the upper surface of the strip and other lateral projections engaging the under surface of the strip, and means for locking the post against rotary movement relative to the strip.

2. In a loose leaf binder, a metallic binder strip having a post upstanding therefrom, the lower end of the post having tongues

extending at right angles to the post axis ¹⁰ and countersunk in the under side of the strip, and means for preventing displacement of the post downwardly.

In testimony that I claim the foregoing I have hereunto set my hand at Milwaukee, in the county of Milwaukee and State of Wisconsin. ¹⁵

EMIL H. FISCHER.
